DESIGN FOR A GAME BOARD

Bennett Lewis, New York, N. Y.

Application November 8, 1938, Serial No. 80,952

Term of patent 3½ years

To all whom it may concern:

Be it known that I, Bennett Lewis, a citizen of the United States, residing in New York city, in the county of New York and State of New York, have invented a new, original, and ornamental Design for a Game Board, of which the following is a specification, reference being had to the accompanying drawing, forming part thereof.

The game board is of no appreciable or material thickness.

The figure is a plan view of the game board, showing my new design.

I claim:

The ornamental design for a game board, substantially as shown and described.

BENNETT LEWIS.
